(57) **CLAIM**

The ornamental design for a charger for remote control, as shown and described.

DESCRIPTION

FIG. 1 is a front, right side, perspective view of a charger for remote control showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a reference view showing the claimed design portion mounted from unclaimed subject matter for the purpose of illustrating the environment in which the article embodying the design is used.

The broken lines in FIG. 8 are for illustrative purposes only and form no part of the claimed design.

1 Claim, 5 Drawing Sheets
